George W. Crowder
by
A. K. Evans, Jr.

UNITED STATES PATENT OFFICE.

GEORGE WASHINGTON CROWDER, OF GOLDTHWAITE, TEXAS.

SPRING BED-BOTTOM.

SPECIFICATION forming part of Letters Patent No. 511,513, dated December 26, 1893.

Application filed August 1, 1893. Serial No. 482,094. (No model.)

To all whom it may concern:

Be it known that I, GEORGE WASHINGTON CROWDER, a citizen of the United States, residing at Goldthwaite, in the county of Mills 5 and State of Texas, have invented certain new and useful Improvements in Spring Bed-Bottoms, of which the following is a full, clear, and exact description, reference being had to the accompanying drawings, and to letters of 10 reference marked thereon, forming a part of this specification.

My invention relates to spring bed bottoms.

It has for its object to provide a spring bed 15 bottom, which shall be simple of construction, durable in use, and comparatively inexpensive of production.

With these objects in view, the invention 20 consists in certain features of construction and combination of parts of the same which shall be hereinafter described and claimed.

In the drawings, Figure 1 is a side view of 25 a bed frame with one of the side rails removed to more clearly show my invention, and Fig. 2, is a top plan view of the same.

In the drawings the letter A, denotes the 30 bed frame which may be of any well known or improved construction. B, denotes the slats, and C denotes the springs. Each of 35 these springs is made of ordinary bed spring wire, and can be of any desired size and shape, and each is provided at its lower end with a spring clamp D, by means of which it is securely held in position on a bed slat.

The spring clamps are made integral with 40 the spring proper, and each is formed by bending the lower coil outward a suitable distance, and then inward, terminating in an outwardly projecting end E, which latter is situated approximately parallel to the vertical axis of the spring. The upper coil of 45 each of said springs is bent outward as shown at F, then laterally as shown at G, then backwardly as shown at H, again laterally as shown at I, and then rearwardly again as shown at J, where it is formed with a hook K. By this construction, one spring may be 50 hooked to the adjacent spring on the same slat, and then to the spring oppositely as

shown clearly in Fig. 2, the several bends in 50 the spring filling up the space which would otherwise be left between each four of the springs.

It will be seen that the bed bottom may 55 be easily removed, by detaching the springs from each other, when the slats may be lifted clear out of the bedstead without bodily removing the bed bottom, thus enabling a delicate person to easily take apart and clean the 60 bed.

L, denotes spring clamps secured to the ends of each of the end slats.

M, denotes the head braces the ends of which are in hook form, and the upper ends of which are hooked into eyes screwed in the 65 head board of the bed and the lower ends hooked into the adjacent springs. These brace rods are preferably curved to give to the mattress a curvature so that the pillows may be properly placed.

N, denotes the foot braces which are hooked in eyes screwed to the under edge of the foot board, and to the lower springs. By this manner of fastening the springs it will be 70 evident that they will retain their shape and 75 not sag out of position, they being firmly braced and held in place.

From the foregoing description taken in connection with the accompanying drawings, the operation and advantage of my invention 80 will be readily understood. The bed bottom is simple, it is easily secured in position, and is easily removed for the purpose of packing or cleaning.

Having thus described my invention, what 85 I claim, and desire to secure by Letters Patent of the United States, is—

The combination with the frame and the slats of a separate series of separate and independent coiled springs C on each slat and 90 formed with clamps at their lower ends engaging the slats the upper coils of the springs being extended laterally in loop form into the spaces between each four springs and provided with arms or extensions J approximately parallel with the outer members and projecting beyond the bows of the loops 95 passed under and over the upper coils of the

adjacent spring and extending thence to the
spring of the next succeeding slat and there
formed with an open hook detachably engag-
ing the upper coil of the last named spring,
5 and hooks mounted on the head and foot of
the bed frame and detachably engaging the
upper coils of the end rows of springs, where-

by any single spring or any series of springs
or all of the springs may be simultaneously
removed, substantially as herein described.

GEORGE WASHINGTON CROWDER.
